UNITED STATES PATENT OFFICE.

JOSEPH TWYMAN, OF CHICAGO, ILLINOIS, ASSIGNOR TO THE TWYMAN DECORATING COMPANY, OF SAME PLACE.

DESIGN FOR WALL-PAPER.

SPECIFICATION forming part of Design No. 22,103, dated January 10, 1893.

Application filed December 2, 1892. Serial No. 453,890. Term of patent 7 years.

To all whom it may concern:

Be it known that I, JOSEPH TWYMAN, a citizen of the United States, residing at Chicago, in the county of Cook and State of Illinois, have invented and produced a new and original Design for Wall-Paper, of which the following is a specification, reference being had to the accompanying drawing, which is made a part hereof, and which shows a portion of a strip of wall embodying the new design.

The leading feature of the design is a slender stem laid in graceful lines and curves that do not carry it far to either side of a straight line, and a number of willow leaves branching therefrom in different directions, the whole being so disposed that the design suggests a single continuous branch of a vine occupying a vertical position.

In the drawing, *a* represents the stem, which is continuous and slender and is laid in graceful undulating lines, and *b* represents the leaves, which resemble willow leaves, somewhat, and branch out from the stem in different directions. Some of them incline upward and others droop and hang down, some of them cross and hide the stem and others cross each other.

What I claim is:—

The design for wall paper, substantially as herein shown and described.

JOSEPH TWYMAN.
